(57) **CLAIM**

I claim the ornamental design for a stringed instrument, as shown and described.

DESCRIPTION

FIG. 1 is a perspective view of a stringed instrument showing my new design;

FIG. 2 is a front view thereof;

FIG. 3 is a rear view thereof;

FIG. 4 is an elevational view taken along lines 4—4 in FIG. 2;

FIG. 5 is an elevational view taken along lines 5—5 in FIG. 2;

FIG. 6 is an elevational view taken along lines 6—6 in FIG. 2; and,

FIG. 7 is an elevational view taken along lines 7—7 in FIG. 2.

The broken lines shown are for illustrative purposes only and form no part of the claimed design.
